UNITED STATES PATENT OFFICE.

JOHN NEUBERGER AND JAMES F. HINES, OF CLEVELAND, OHIO.

SHADE AND CURTAIN-POLE SUPPORT.

1,074,973.

Specification of Letters Patent.

Patented Oct. 7, 1913.

Application filed April 17, 1913. Serial No. 761,741.

To all whom it may concern:

Be it known that we, JOHN NEUBERGER and JAMES F. HINES, citizens of the United States, residing at Cleveland, in the county 5 of Cuyahoga and State of Ohio, have invented certain new and useful Improvements in Shade and Curtain-Pole Supports, of which the following is a specification.

This invention relates to shade and curtain pole supports or hangers, and has for 10 its object to provide an improved and simple device which will hold a shade roller and curtain pole in position on a window casing, in such manner that they may be 15 swung out or away from the casing to permit convenient access to the window when desired.

The supporting devices are pivoted at one 20 side of the casing to swing horizontally, by means of a support or bracket having a depending pivot pin which fits in a socket piece or fixture attached to the window casing.

In the accompanying drawings—Figure 1 25 is a front elevation illustrating the device. Fig. 2 is a side view of the keeper for the free end of the pole. Figs. 3, 4 and 5, are side and top views of a fixture for holding the shade roller. Fig. 6 is an enlarged view 30 of the pivoted fixture for the curtain pole. Fig. 7 is a top view of the same.

Referring specifically to the drawings, 20 indicates the window casing, to one side of which is attached a socket fixture 8 which 35 receives the pivot pin 7^a depending from the underside of the pole fixture 7. This fixture comprises a curved plate having at one end a loop or ring 7^b through which the pole 6 is inserted, and at the other end a hole 7^c 40 to receive a screw to fasten the pole to the plate. The pole may be swung on the pin 7^a as a pivot to swing toward or from the window. The free end of the pole, when it is swung to the window is received between

the forked arms of a fixture 11 screwed into 45 the opposite side of the window. A chain 9 is attached on the free end of the pole for convenience of manipulation.

The pole supports the shade fixtures 10, each of which consists of an arm projecting 50 from a curved part 10^a which fits over the top of the pole and may be held in place by screws in notches 10^b in the plate. The shade fixture may be made with two arms, as 55 shown in Fig. 3, for the purpose of supporting two curtains if desired.

The shade fixtures being mounted on the pole swing therewith. Accordingly when 60 swung out with the pole the shade and the curtain are removed from the window permitting convenient access for cleaning or 65 washing and also for ventilation and avoiding the trouble of taking down the curtain when the windows are washed, or the room is to be ventilated. The fixture 7 will support a pole of any length, and to put the device in place it is only necessary to attach the fixtures 7 and 10 to the pole, attach the socket piece 8 to the casing, put up the 70 keeper 11, and set the pole in place. The curtain and shade can be completely removed by lifting the pole to remove the pivot pin from the socket.

What we claim is:

75

The combination of a socket piece adapted for attachment to one side of a window casing, a plate having a depending pivot pin fitting in the socket, a pole attached to the plate, and shade holding fixtures secured to 80 the pole.

In testimony whereof we do affix our signatures in presence of two witnesses.

JOHN NEUBERGER.
JAMES F. HINES.

Witnesses:

JOHN A. BOMMARDT,
J. B. DANS.

DISCLAIMER.

1,074,973.—*John Neuberger and James F. Hines, Cleveland, Ohio. SHADE AND CURTAIN-POLE SUPPORTS.* Patent dated October 7, 1913. Disclaimer filed April 28, 1917.

Hereby disclaim:

“Being the joint inventors of the invention set forth in said Letters Patent No. 1,074,973, and the said John Neuberger disclaims being the inventor of any part thereof.”
